UNITED STATES PATENT OFFICE.

LORENZO HENRY, OF LONDON, ENGLAND.

SINGLE-TRIGGER MECHANISM

SPECIFICATION forming part of Letters Patent No. 719,331, dated January 27, 1903.

Application filed July 29, 1902. Serial No. 117,475. (No model.)

To all whom it may concern:

Be it known that I, LORENZO HENRY, gentleman, a subject of the King of England, residing at 79 Grosvenor street, London, W., England, have invented a certain new and useful Improvement in Single-Trigger Mechanisms, of which the following is a full, clear, and exact description, and for which I have applied for Letters Patent in Great Britain, 5 dated December 23, 1901.

This invention relates to an improved single-trigger mechanism for double-barreled firearms, and is applicable to either hammer or hammerless guns.

15 The invention consists, essentially, of a transverse sliding bar mounted in supports secured upon the trigger-blade and capable of protruding from either side of the blade under the sear of the hammer on that side, so 20 that when the trigger is pulled and the trigger-blade raised the corresponding hammer will be released, and when the sliding bar has been brought back and projected from the opposite side of the trigger-blade and the 25 latter is again raised the other sear will be raised and its hammer released.

A further portion of my invention consists 30 in a device which latches the aforesaid sliding bar in position, this latching device being depressed and the bar consequently freed either by automatically striking the top action-plate immediately after the first barrel 35 has been fired or by a separate hand-operated device for cutting out the first barrel when it is desired to fire only the second.

The invention is illustrated upon the accompanying drawings, in which

Figure 1 is a longitudinal elevation of the lock of the gun, both lock-plates being removed. Fig. 2 is an elevation of the trigger-plate seen from the other side and removed from the lock of the gun. Fig. 3 is a plan of Fig. 2. Figs. 4 and 5 are similar views to Fig. 3 and show the successive movements of the sliding bar. Figs. 6, 7, and 8 are end elevations of the rear portions of Figs. 3, 4, and 5, respectively. Fig. 9 is an end view of the lock of the gun, showing the lock-plates, the sears, and the position of the bar under the left sear. Fig. 10 is a similar view, but shows the arrangement of the parts after the left barrel has been fired and immediately before

the latch has struck the top plate a second time. Fig. 11 is a similar view to Figs. 9 and 10, but shows the sliding bar under the right 55 sear ready to fire the right barrel. Fig. 12 shows in elevation a device for cutting out the first barrel when it is desired to fire only the second barrel. Fig. 13 is a plan of the ordinary thumb-lever for breaking open the 60 gun and fitted with connections for setting the transverse sliding bar. Fig. 14 illustrates the movements of the parts shown in Fig. 13. Fig. 15 shows in longitudinal section the slide under the thumb-lever. Fig. 16 is a longitudinal elevation of the transverse sliding bar. Figs. 17 and 18 are front and rear elevations of the sliding latch. Fig. 19 shows the sliding latch in its intermediate position.

On the annexed drawings I have shown my 70 invention applied to a double-barreled gun in which the left barrel is fired first. Obviously, however, the device may be so constructed that the right barrel is fired first.

Upon the box *a* of the trigger-plate *b* a trigger-blade *c* is pivoted at *c'*. On the blade *c* at its rear are screwed or secured side plates *d* *d'*, and in these side plates is mounted a transverse sliding bar *e*, having an approximately central collar *f*. This bar *e* is of such 80 length that it can project outwardly from either side of the plates *d* *d'*, its stroke being limited by the collar *f*, and when one end is projecting fully on one side its other end is approximately flush with the other side, as 85 will be clearly understood from Figs. 3, 4, 5 and 6, 7, 8.

Upon the bar *e* is mounted a coil-spring *f'*, which is shown in Figs. 3 and 6 compressed between the collar *f* and the left side plate 90 *d'*, so that this spring normally tends to drive the bar *e* out from the right-hand side, as shown in Fig. 8.

Upon the trigger-blade *c* is pivoted at *c'* a bell-crank lever, one arm *g* of which engages 95 with a hole in the collar *f*. By suitably operating the other arm *g'* of the bell-crank it will be understood that the bar *e* can be driven out, so as to project from the left side plate *d'*, and when this arm *g'* is freed unless the bar *e* is held the spring *f'* will drive the said bar *e* in the opposite direction. Various means may be employed to actuate this arm *g'*, operated either directly or indirectly by

the mechanism of the locking-bolt of the gun. As an example I have shown at Fig. 2 a slide *h* secured to the box *a* on the trigger-plate by means of a screw working in a slot *h'*, this slide having at one end an arm *i*, fitted with a rod *i'*, on which is mounted a coiled spring *k*. The slide *h* at its other end can bear against the lever-arm *g'*, and it will be evident that if the slide *h* be pushed back the bell-crank lever will be operated and its arm *g* moved across the trigger-blade from the position shown in Fig. 5 to that shown in Fig. 3. The slide *h* may be operated in any suitable manner and is here shown actuated by the ordinary locking-bolt *l*, operated by the usual thumb-lever *l'* in the usual manner.

The spring *k* is mounted for only a portion of its length on the rod *i'* and is continued beyond the rod and through the box *a* of the trigger and bears against the blade *c* above the pivot *a'*, as shown in Fig. 1. This spring *k* therefore acts as the trigger-spring and replaces the ordinary leaf-spring for the trigger.

The working of the thumb-lever and of the locking-bolt is illustrated and will be perceived from Figs. 13, 14, and 15. The upper part of the action-plate *a''* is grooved longitudinally, and a slide-bolt *m* is capable of sliding in this groove. The thumb-lever *l'* is fulcrumed eccentrically at *f'*, and the screw *m'*, by which the lever *l'* is secured in position, is screwed into a boss *m''*, upstanding from the slide *m*. The slide *m* is also rigidly connected, by means of a screw or rivet *n'*, 35 with the arm *n* of the ordinary locking-bolt *l*. The arm *n* is extended rearwardly of the locking-bolt *l* as a rod *o*, journaled and slideable in a hanger *o'*, secured to the underside of the action-plate *a''*, the arm *n* and rod *o* being rigidly connected together. A coiled spring *o''* is mounted upon the rod *o* and tends to return the thumb-lever *l'* and locking-bolt *l* to their normal positions, as shown in Figs. 1 and 13. It will thus be seen that when the thumb-lever *l'* is moved sidewise in the ordinary manner to break open the gun (see Fig. 14) the slide-bolt *m* is drawn rearward, and this by means of arm *n* and bolt *l* pushes the slide *h* rearwardly, (compressing spring *k*), 45 and the slide *h* acting on lever-arm *g'* the other lever-arm *g* will carry the sliding bar *e* over to the position shown in Fig. 3, the spring *f'* being compressed upon the bar *e*. When the gun has been loaded and the thumb-lever *l'* 55 returned to its normal position, Fig. 13, the slide *h* will be returned to the position indicated in Figs. 3, 4, and 5 by means of the spring *k*. The transverse sliding bar *e* being held in the position of Fig. 3 by a latch hereinafter described, upon pulling the trigger the bar *e* will be raised with the trigger-blade and will raise the left sear, thereby discharging the left barrel, and when this latch has 60 been disengaged the bar *e* will be freed and finally pass to the position of Figs. 5 and 11. Upon pulling the trigger a second time, therefore, the right sear will be raised and the

right barrel fired. I have, however, shown fitted to the mechanism a latch, which arrests the transverse movement of the sliding bar *e* at about the middle of its passage across the plates *d d'*, mounted on the trigger-blade, and which latch is disengaged from the bar *e* only after the first barrel has been fired.

The left-hand side plate *d'* on the trigger-blade is prolonged upwardly and is grooved on both faces. The outer face receives the sliding latch *p*, the edges of which are preferably beveled off, and the edges of the groove in which it travels are correspondingly undercut, so as to hold the beveled edges of the said latch. The inner groove of the extension *d'* is fitted with a guide-rod *q*, upstanding from the extension *d'* and fitted with a coil-spring *q'*. The latch *p* is provided with a recess *p'* near its lower part. Its upper part is rounded off and its rear side is provided with a block *p''*, hollowed out and capable of engaging and sliding upon the aforesaid guide-rod *q*. If the latch *p* is depressed, the block *p''* travels in the groove upon the inner face of the extension *d'*, as clearly shown in Fig. 2. The latch *p* is shown separately in front and rear elevations in Figs. 17 and 18.

The transverse sliding bar *e*, which is preferably of round section, is shown separately at Fig. 16. It will be seen that its end toward the left of the figure is provided with a recess *r'* upon its upper side, forming a hook *r* and bents *e'* and *e''* upon its lower side, the bent *e''* being shown inclined and the bent *e'* being nearer the collar *f*. The hook of the bar *e*, the bent *e'*, and the bent *e''* thus form three steps for engagement with the base or ledge *v* of the recess *p'*. The recess *p'* in the latch *p* thus engages the bent *e''*, while the bar *e* is in position for firing the first barrel, Fig. 6, and the bent *e'* when the bar is in the intermediate position, Fig. 7. The latch *p* is depressed, thereby temporarily freeing the bar *e* by its upper rounded end striking against the under side of the action-plate *a''* when the trigger-blade is raised. The spring *q'* acts upon the block *p''*, and this tends to force the latch *p* upward. In the position shown in Fig. 1 the ledge *v* engages the bent *e''*, as will be seen by comparing Figs. 6 and 7. Upon pulling the trigger the pivoted trigger-blade is raised and the left sear *s* lifted by the left-hand end of the bar *e*. The raising of the left sear effects the discharge of the left barrel and the latch strikes against the under side of plate *a''*. This striking action depresses the latch *p* in its slide or support *d'* and the ledge *v* is forced out of the bent *e''*. The spring *f'*, acting on the collar *f*, thereupon drives the bar toward the right; but the hook or projection *r* upon the bar *e* meets the flange of the left sear, as will be understood from Fig. 9. The ledge *v* of the latch now engages the incline of the bent *e'*, (see Figs. 7 and 19,) and when the trigger-blade is lowered sufficiently the

projection *r* will be disengaged from the sear and the ledge *v* will enter the bent *e'* farther. The rebound of the gun from the shoulder (due to the discharge of the first barrel) takes 5 place immediately, and the latch *p* again striking the plate *a''* during this involuntary pull upon the trigger the ledge *v* is depressed out of the second bent *e'*, the spring *f'*, which still acts on the collar *f*, tending to drive the 10 bar *e* again to the right; but during this second raising of the trigger-blade (the involuntary pull occurs while the trigger-blade is still in its upper position) the bar *e* when wholly released from the latch *p* meets the 15 face of the right sear *s'*, and when the trigger-blade falls, owing to the trigger being released, the bar *e* falls therewith, making rubbing contact with the right sear *s'*, until it assumes the position shown in Fig. 10, when 20 the spring *f* is free to thrust out the bar *e* to its full extent—*i.e.*, as fully as is permitted by the collar *f*—under the right sear. Upon again pulling the trigger the right sear *s'* will be raised and the right hammer fired. 25 The lock-plates, the hammers, and their sears may be of the usual construction, so that they need not be further referred to. The sears *s* and *s'*, however, are shown without the usual inwardly-projecting tails, since 30 I find the tails are unnecessary with my single-trigger device.

In case it should be desired to fire the second barrel only and without previously firing the first barrel I arrange a thumb-piece or 35 slide *t* upon the plate *a'*, covering a slot *t'* in the said plate and rigidly connected with a stud *u* of suitable depth by means of a pin *u'*. This stud is normally out of contact with the latch *p*; but if instead of raising the trigger-blade to meet the action-plate *a''* the thumb-piece *t* and stud *u* be pulled back the said 40 stud will depress the latch sufficiently to free the bar *e* and allow it to project under the right sear, thus cutting out the left barrel. 45 The lower position of the latch *p* is shown in dotted lines on Fig. 12, and the thumb-piece will then be returned to its normal position.

Having thus described my invention, what I claim as such, and desire to secure by Letters Patent, is—

1. In a single-trigger mechanism, the combination with the sears and a trigger-blade fast to a trigger, of a sliding bar transverse of and in part protrusile from said blade, a spring 55 encircling said bar and tending to force it to one side, and means operated by the movement of the trigger for forcing it toward the other side against the tension of the spring, substantially as described. 60 2. In single-trigger mechanism the combination with the sears and a trigger-blade fast to a trigger, of side plates secured upon said blade, a sliding bar mounted transversely in said side plates, a collar upon said bar, and a 65 spring bearing on said collar and a latch for holding and releasing said bar.

3. In single-trigger mechanism, the combi-

nation with the sears and a trigger-blade fast to a trigger, of side plates secured upon said blade, a sliding bar mounted in said side 70 plates and movable transversely of said blade, a collar upon said bar, a coiled spring upon said bar bearing on said collar and a bell-crank lever pivoted upon said blade, said bell-crank lever having an arm which engages the 75 collar upon said bar and a slide adapted to operate said bell-crank lever.

4. In single-trigger mechanism, the combination with the sears and a trigger-blade fast to a trigger, of a box on the trigger-plate to 80 which said trigger-blade is pivoted, side plates secured upon said blade, a sliding bar mounted in said side plates transversely of said blade, a collar on said bar, a coiled spring upon said bar bearing upon said collar, a bell-crank lever pivoted upon said blade, one arm 85 of said bell-crank lever engaging said collar and the other arm being movable by a slide slidably on said trigger-box.

5. In single-trigger mechanism, the combination with the sears and a trigger-blade fast to a trigger, of a box on the trigger-plate to which said trigger-blade is pivoted, side plates upon said blade, a sliding bar mounted in said side plates transversely of said blade, 90 a collar on said bar, a coiled spring upon said bar bearing on said collar, a bell-crank lever pivoted upon said blade, one arm of said bell-crank lever engaging the aforesaid collar on said bar and the other projecting into the 95 path of a slide secured upon said trigger-box, and an arm to said slide said arm engaging the locking-bolt of the gun.

6. In single-trigger mechanism, the combination with the sears and with a trigger-blade fast to a trigger, of a box upon the trigger-plate to which said trigger-blade is pivoted, side plates upon said blade, a sliding bar mounted in said side plates transversely of said blade, a collar on said bar, a coiled spring upon said bar bearing against said collar, a bell-crank lever pivoted upon said blade, whereof one arm engages the aforesaid collar and the other is movable rearwardly by a slide secured upon said trigger-box, an arm 105 to said slide, a guide-rod from said arm, and a coiled spring upon said guide-rod, said spring extending through the aforesaid box on the trigger-plate and bearing against said trigger-blade above the pivot of said blade. 110

7. In single-trigger mechanism, the combination with the sears and with a trigger-blade fast to a trigger, of side plates secured upon said blade, a sliding bar mounted in said side plates transversely of said blade, a collar 115 upon said bar, a coiled spring upon said bar bearing on said collar, bents upon one end of said bar, a grooved support upstanding from said trigger-blade, a latch secured in said grooved support, a spring upholding said 125 latch, and a recess in said latch whereby the bents in said sliding bar may be engaged. 130

8. In single-trigger mechanism, the combination with the sears and with a trigger-blade

fast to a trigger, of side plates secured upon said blade, a transverse sliding bar mounted in said side plates, a collar upon said bar, a coiled spring upon said bar bearing on said 5 collar, bents upon the under side of said bar, a transverse groove upon the upper side of said bar, an upstanding projection upon the end of said bar formed by said groove, a hollow in the sear with which said projection 10 engages, a support from said trigger-blade, a latch slideable in said support, a spring upholding said latch and a recess in said latch whereby the bents in said bar may be engaged.

9. In single-trigger mechanism, the combination with the sears and with a trigger-blade 15 fast to a trigger, of side plates secured upon said blade, a sliding bar mounted in said side

plates transversely of said blade, a collar upon said bar, a coiled spring upon said bar bearing on said collar, bents upon one end of 20 said bar, an upstanding support from said trigger-blade, a spring-impelled latch secured in grooves in said support, a recess in said latch capable of engaging the bents in said bar, and a slideable thumb-piece upon the upper lock-plate having a dependent stud movable with said thumb-piece, and capable of 25 engaging and depressing said latch.

In witness whereof I have hereunto set my hand in presence of two witnesses.

LORENZO HENRY.
